(57) **CLAIM**

The ornamental design for a hanging light source cover, as shown and described.

DESCRIPTION

FIG. 1 is a front perspective view of the hanging light source cover;

FIG. 2 is a right side view of the hanging light source cover;

FIG. 3 is a front side view of the hanging light source cover;

FIG. 4 is a left side perspective view of the hanging light source cover;

FIG. 5 is a right side perspective view of the hanging light source cover;

FIG. 6 is a top view of the hanging light source cover;

FIG. 7 is a bottom view of the hanging light source cover;

FIG. 8 is a front perspective view of the hanging light source cover hung in an upside down configuration;

FIG. 9 is a right side view of the hanging light source cover hung in an upside down configuration;

FIG. 10 is a front view of the hanging light source cover hung in an upside down configuration;

FIG. 11 is a left side perspective view of the hanging light source cover hung in an upside down configuration;

FIG. 12 is a right side perspective view of the hanging light source cover hung in an upside down configuration;

FIG. 13 is a top view of the hanging light source cover; and,

FIG. 14 is a bottom view of the hanging light source cover. The broken lines shown on the drawings depict environment only and form no part of the claimed design.
